CLAIM

The ornamental design for a belt buckle, as shown and described.

DESCRIPTION

FIG. 1 is a perspective view of the belt buckle;

FIG. 2 is a front view of the belt buckle;

FIG. 3 is a rear view of the belt buckle;

FIG. 4 is a left side view of the belt buckle;

FIG. 5 is a right side view of the belt buckle;

FIG. 6 is a top view of the belt buckle; and,

FIG. 7 is a bottom view of the belt buckle.

The shading lines within the outer periphery lines of the illustrated belt buckle designate its surface area only and no further embellishment or design element.

1 Claim, 6 Drawing Sheets(56)
